VARIABLE LEAD GRIP SLEEVE FOR
MECHANICAL PENCILS

Mark E. Savoie, Cleveland, Ohio

Application August 11, 1949, Serial No. 109,728

4 Claims. (Cl. 120—18)

1

My invention relates to a new and improved lead grip sleeve for propel-retract mechanical pencils capable of receiving and holding any one of many leads of numerous diameters, shapes or lengths.

The present-day market demands many different leads and thus now necessitates a mechanical pencil adapted to receive leads of many different shapes, diameters or lengths. For example, at present there is on the market a standard lead of .045" in diameter, a thin or fine line lead .036" in diameter, as well as round, square and triangular shaped leads. Mechanical pencil manufacturers have been trying for several years to design and build a propel-retract mechanical pencil which will receive and hold any desired one of the above-mentioned leads.

Prior to this time, it has been common in all mechanical pencils, as cited above, that the lead grip sleeve be constructed to hold only one diameter lead. This necessitates the carrying of more than one pencil in one's pocket if they desire the use of a different diameter lead.

Therefore, one of the objects of my invention is to provide a variable lead grip sleeve for a propel-retract pencil which will receive and hold any desired one of many leads of numerous sizes, shapes or diameters.

Another object of my invention is to provide a variable lead grip sleeve for a propel-retract mechanical pencil wherein the lead grip sleeve automatically adapts itself to the desired one of the many shapes, diameters or sizes of leads inserted therein.

Another object of my invention is to form the variable lead grip sleeve of resilient tempered metal with gripping fingers, whereby the fingers automatically grip any desired one of the numerous leads of different lengths, diameters or shapes when the lead grip sleeve is withdrawn by manual operation into the lead grip sleeve guide and helix.

Another object of my invention is to provide the lead gripping fingers of the variable lead grip sleeve with concave surfaces adapted to effectively and grippingly engage the surface of a lead inserted therebetween when the lead grip sleeve is withdrawn by manual operation into the lead grip sleeve guide and helix.

Another object is to provide a propel-retract mechanical pencil with a collet type tip with grip fingers and with a variable lead grip sleeve which will effectively cooperate to grip any desired one of many leads of numerous lengths, shapes or diameters when the collet type tip is under spring tension.

2

Other objects and a fuller understanding of my invention may be had by referring to the following description and claims, taken in conjunction with the accompanying drawings, in which:

Figure 1 is an enlarged, broken elevational view, partly in cross-section, of my mechanical pencil having the improved lead holder;

Figure 2 is a fragmentary elevational view 10 similar to that of Figure 1 with a lead inserted in the pencil;

Figure 3 is a cross-sectional view along the line 3—3 of Figure 1;

Figure 4 is a plan view of the lead holder used 15 in my pencil;

Figure 5 is a view along the line 5—5 of Figure 4;

Figure 6 is a view along the line 6—6 of Figure 4; and

Figure 7 is an elevational view of the lead holder with an ejection pin therein.

My new, improved lead grip sleeve, capable of receiving and holding any one of many leads of numerous diameters, shapes or sizes, is enclosed 25 in a pencil barrel 10 having a hollow pencil tip 11 fastened to one end thereof. In my assembled propel-retract mechanical pencil, I provide a lead chamber or guide tube 12 fitted in a helix 13 and slidably carrying therein my new lead holder or grip sleeve 14. The lead chamber or guide tube 12, illustrated in Figures 1 and 2 as a collet type member, extends through the hollow tip 11 and is disposed for reciprocal movement axially of the pencil barrel 10 in an inward direction and in an outward direction relative to the hollow pencil tip.

I have provided the pencil barrel with an axially internally grooved or splined sleeve 15. The lead chamber or guide tube 12 is supported for axial movement by a toothed ring 16, which cooperatively engages the grooves on the inside of the sleeve 15. This toothed ring 16 may be press-fitted on the lead chamber or guide tube 12 or fastened thereto by any suitable means whereby the lead chamber does not rotate relative to the pencil barrel. The lead grip sleeve 14 is axially slidable within the lead chamber 12 to propel or retract a lead out of or into the lead chamber 12. The lead grip sleeve 14 has a pin 17 which extends outwardly through an elongated slot 18 in the lead chamber to engage the helix 13. The helix 13 is manually rotatable relative to the lead chamber or guide tube 12 to axially propel or retract the lead grip sleeve 14. The collet type lead chamber or guide tube 12 has axially extended grip tip portions 19, which

may be extended outwardly beyond the pencil tip 11 when the pencil is assembled. These grip tip portions 19 are designed to engage under spring tension any one of many leads of numerous diameters, shapes or sizes which may be inserted in and received by the lead chamber 12. The lead chamber 12 and the extended grip tip portions 19 are constructed of resilient material whereby the grip tip portions are normally divergent and tend to radially spread.

A spring member 20 is disposed within the pencil tip end of the pencil barrel and is assembled with the lead chamber to urge the lead chamber in the inward direction. In Figure 2 of my drawings, I illustrate the lead chamber being urged in the inward direction with the grip tip portions 19 in cammed engagement with the pencil tip 11 and gripping a pencil lead 29. The spring member 20 is axially compressed to move the lead chamber 12 in the outward direction relative to the pencil barrel 10 to release the collet type grip on the lead.

The spring member 20 is kept in proper alignment in the pencil barrel by means of spring guide members 21 and 22. The guide member 21 abuts the geared bushing 16 and the guide member 22 abuts the pencil tip 11 with the spring 20 disposed therebetween and normally tending to separate the guide members.

The helix 13 is disposed on the backside of the geared bushing 16 or on the rear end of the lead chamber 12. The helix 13 is fastened to the lead chamber 12 by abutting the end of the helix with a washer 23 and crimping the end of the lead chamber 12. In Figures 1 and 2 of my drawings, I best illustrate that the helix 13 moves axially with the lead chamber 12 when the lead chamber 12 is axially moved relative to the pencil barrel. The helix 13 may also be rotated relative to the lead chamber 12 by an operating sleeve 24, which extends out of the eraser end of the pencil barrel 10 to support an eraser 25. A sleeve 26 is tightly fitted on to the end of the helix 13 nearest the toothed ring 16 and engages the operating sleeve 24, as illustrated in Figures 1 and 2. This sleeve 26 extends beyond the end of the helix 13 to engage the toothed ring 16 and thereby provide a space between the ring 16 and the helix 13.

As is best illustrated in Figures 4, 5 and 6 of my drawings, the lead holder 14 is preferably constructed from a stamping or flat sheet of material. In Figures 4, 5 and 6, I illustrate the blank which may be rolled to form the lead holder 14. This blank is an elongated rectangular piece, having a slot 28 therein and the pin 17 on the surface thereof, and at one end of the slot 28. Although I have illustrated that this pin 17 may be formed by partially punching through the blank, it is understood that a separate piece of material may be used and welded to the blank. The slot 28 extends longitudinally of the blank, which will form the lead holder 14 and is disposed at one end thereof. I have provided the other end of the lead holder 14 with fingers 30. These fingers 30 extend axially of the lead holder or lead grip sleeve 14 and are slightly bowed, as illustrated in Figures 1, 2 and 7. The lead grip sleeve and the axially extended bowed fingers are preferably constructed of resilient material for gripping a lead inserted therebetween. For purposes of description, each of the fingers 30 is described as having a bowed portion 31 terminating in a tip portion 32. The tip portions 32 extend radially outward from the axis of the grip

sleeve 14 so that a lead may be forced therebetween. I have also constructed the fingers 30 slightly concave to provide a concave lead engagement surface 33, as illustrated in Figure 6, to provide tightly frictional engagement of the fingers on a lead inserted therebetween.

The lead holder or lead grip sleeve 14 supports a push pin 34 axially movable therein and having a lug 35 extending outwardly through the slot 28. The lug 35 engages the helix 15 to axially move the push pin 34 in and out of the space between the fingers 30 upon rotation of the helix 13. In Figure 1, I illustrate the push pin pushed so that it extends outwardly through the fingers 30 and through the grip tip portions 19 of the lead chamber 12. Thus, any lead in the lead chamber or between the fingers 30 may very easily be removed therefrom. Turning of the operating sleeve 24 and thereby the helix 13 relative to the pencil barrel 10 retracts the push pin 34 into the lead holder 14, as illustrated in Figure 2, and positions the lug 35 against the end of the slot 28. When the lug 35 hits the end of the slot 28, further turning of the helix 13 moves the pin 17 on the lead holder into the helix 13, thus permitting the lead holder 14 to be retracted into the pencil. A lead inserted in the fingers 30 of the lead holder 14 will be drawn or retracted into the pencil.

The push pin 34 is put in the lead holder 14 with the lug 35 extending through the slot 28 during the construction of the lead holder 14. The blank illustrated in Figure 4 is rolled around the push pin therein, as illustrated in Figure 7. The axial movement of the push pin relative to the lead holder or lead grip sleeve is sufficient to permit the push pin 34 to be propelled through the grip tip portions 19 of the lead chamber 12. The bowed portions 31 of the fingers 30 engage the inner surface 36 of the lead chamber or guide sleeve 12 and are tended to be flattened out thereby to grip a lead. With my lead holder 14 having the bowed fingers 30 cooperatively engaging the inner surface 36 of the lead chamber 12, I can use any desired lead of the different leads presently sold on the market.

In using my mechanical pencil, the operating sleeve 24 may be pushed axially of the pencil barrel 10 to move the lead chamber 12, the helix 13, and the lead holder 14 in an outward direction, permitting sliding and expanding of the grip tip portions 19. Rotation of the operating sleeve 24 rotates the helix 13 relative to the lead chamber 12 to axially move the lead grip sleeve 14 and the push pin 34 therewith. The operating sleeve 24 may be simultaneously moved axially of the pencil barrel 10 to release the gripping pressure of the grip tip portions 19 on a lead and rotated to either propel or retract the lead grip sleeve and a lead inserted therein.

Although my invention has been described in its preferred form with a certain degree of particularity, it is understood that the present disclosure of the preferred form has been made only by way of example and that numerous changes in the details of construction and the combination and arrangement of parts may be resorted to without departing from the spirit and the scope of the invention as hereinafter claimed.

What is claimed is:

1. In the propel-retract mechanism of a pencil adapted to receive any one of many leads of numerous diameters, shapes or sizes, a guide tube having a slot extending longitudinally thereof, a helix turnable about said guide tube, and a

lead grip sleeve slidable in said guide tube and having a projection extending through the slot and operably engaging said helix, said lead grip sleeve having axially extended bowed fingers of resilient material for gripping a lead inserted therebetween.

2. In the propel-retract mechanism of a pencil adapted to receive any one of many leads of numerous diameters, shapes or sizes, a helix, a lead grip sleeve having axially extended fingers of resilient material, said fingers having outwardly bowed portions and lead gripping portions, and a guide tube in said helix and axially slidably receiving said lead grip sleeve therein and flattening the said resilient outwardly bowed portions thereby causing said lead gripping portions to grip a lead inserted therebetween, said guide tube having a longitudinal slot therein, said lead grip sleeve having a projection extending through said slot and engaging said helix to effect axial sliding of the lead grip sleeve in the guide tube upon turning of the helix relative to the guide tube.

3. In the propel-retract mechanism of a pencil adapted to receive any one of many leads of numerous diameters, shapes or sizes, a helix, a lead grip sleeve having axially extended fingers of resilient material, said fingers having outwardly bowed portions and lead gripping portions, a guide tube in said helix and axially slidably receiving said lead grip sleeve therein and flattening the said resilient outwardly bowed por-

tions thereby causing said lead gripping portions to grip a lead inserted therebetween, said guide tube having a longitudinal slot therein, said lead grip sleeve having a projection extending through said slot and engaging said helix to effect axial sliding of the lead grip sleeve in the guide tube upon turning of the helix relative to the guide tube, and means for slidably moving said lead through the lead grip sleeve and outwardly through the pencil tip.

4. In the propel-retract mechanism of a pencil adapted to receive any one of many leads of numerous diameters, shapes or sizes, a guide tube terminating at the outer end thereof in a resilient grip tip, and a sleeve slidable in guide tube and having axially extended bowed fingers of resilient material for gripping a lead also gripped by said grip tip at a longitudinally spaced point from said grip tip.
